UNITED STATES PATENT OFFICE.

JOHN W. DUNLAP, OF MAQUOKETA, IOWA.

METALLIC FENCE POST.

Application filed May 4, 1927. Serial No. 188,752.

This invention has reference to metallic posts, and more particularly posts employed in the construction of fences, the primary object of the invention being to provide 5 novel means whereby the wire mesh of which the fence is formed, may be secured to the posts without the use of nails, staples or other securing means.

Another object of the invention is to construct a fence post which will be exceptionally strong and durable and one which will be securely anchored in the ground surface against lateral movement.

With the foregoing and other objects in view which will appear as the description proceeds, the invention resides in the combination and arrangement of parts and in the details of construction hereinafter described and claimed, it being understood 20 that changes in the precise embodiment of the invention herein disclosed, may be made within the scope of what is claimed, without departing from the spirit of the invention.

25 Referring to the drawing:

Figure 1 is an elevational view illustrating a fence post constructed in accordance with the invention and showing the fence wire as secured thereto.

30 Figure 2 is a side elevational view of the post.

Figure 3 is a fragmental enlarged elevational view of the post.

35 Figure 4 is a sectional view taken on line 4-4 of Figure 3 and showing a wire as secured thereto.

Referring to the drawing in detail, the post includes a metallic body portion having a forward flange 5, a rear flange 6 and lateral flanges 7 extending throughout the 40 length of the body portion as clearly shown by the drawing.

The forward flange 5 is provided with notches extending from the forward edge thereof and terminating adjacent to the central portion of the post, the notches extending inwardly and upwardly as at 8 and downwardly as at 9, terminating in substantially straight portions 10, the notches 45 being arranged predetermined distances apart to receive the wires 14 of the wire

mesh material of the fence to secure the wire mesh material to the post in a manner to eliminate the necessity of bending the wire mesh material.

55 Adjacent to the base of the post is a notch that extends inwardly from the outer edge of the forward flange 5 as at 11, and upwardly adjacent to the central portion of the post at 12, thereby providing a locking 60 slot for the lowermost strand 15 of the wire mesh material.

The forward flange 5 is also provided with a slot to accommodate the anchor plate 13, which has inclined outer edges so that the 65 post may be driven into the ground surface, the plate 13 preventing the post from being loosened.

From the foregoing it will be seen that to position the wire mesh material of a fence, 70 the lower strand of wire is positioned in the cut out portion 12 and the wire mesh material lifted and moved to a position in parallel relation with the post.

The wires of the wire mesh material will 75 fall opposite to the slots formed in the flange 5 whereupon the wire mesh material is dropped to the end that the wire mesh material will move downwardly within the portions 10 of the notches, to be locked in position and may only be removed by elevating the wire mesh material, until the wire strands thereof may be moved laterally from their positions within the cut out portions.

80 When the wire mesh material is secured 85 in its proper position, the lower strand is held within the upwardly disposed elongated portion of the lowermost notch.

Thus it will be seen that due to this construction, the wire mesh material of a fence 90 may be securely fastened to the post without the use of nails, staples or other securing devices and may be readily removed in case of repair.

95 It will also be obvious that the cross sectional construction of the post insures an exceptionally rigid post structure which will not bend under the usual strains to which a fence and fence post are subjected.

I claim:

100 In a metallic fence post, a body portion having a forward flange and lateral flange,

said forward flange having notches extending upwardly at oblique angles and downwardly at oblique angles, terminating in vertical downwardly extended portions, said forward flange having a lower lock notch extending inwardly from the outer edge thereof and terminating in an elongated upward-

ly extended portion, said notches adapted to receive wires of a wire mesh fence, the wires being stretched to points within the notches.

In testimony that I claim the foregoing as my own, I have hereto affixed my signature.

JOHN W. DUNLAP.
